UNITED STATES PATENT OFFICE.

FLORA D. LONGENHELT, OF ONEIDA, NEW YORK.

DESIGN FOR A DIAL FOR CLOCKS AND WATCHES.

SPECIFICATION forming part of Design No. 21,290, dated January 12, 1892.

Application filed November 6, 1891. Serial No. 411,101. Term of patent 7 years.

To all whom it may concern:

Be it known that I, FLORA D. LONGENHELT, of Oneida, in the county of Madison and State of New York, have invented and produced a new and original Design for a Dial and Hands, of which the following is a specification, reference being had to the accompanying drawing, which shows a front face view of the clock face or dial and the hands.

- 10 The leading features of my design consist in representations by symbols of Faith, Hope, and Charity, the cardinal virtues, in front of or surmounting a clock-face A, subdivided equally into the four scriptural watches.
- 15 Thus the central heart *a* is the symbol of Charity, the anchor *b* upon the hour-hand is

the symbol of Hope, and the cross *c* upon the minute-hand is the symbol of Faith; also, the single star *d* is the sign of the first watch, the double star *e* the sign of the second watch, ^{2c} the treble stars *m* are the sign of the third watch, and the quadruple stars *n* are the sign of the fourth watch.

What I claim is—

The design for dial and hands, as herein described and shown.

In witness whereof I have hereunto set my hand this 26th day of October, 1891.

FLORA D. LONGENHELT.

In presence of—

M. E. HITCHCOCK,
A. B. FRENCH.
